ATTORNEY

UNITED STATES PATENT OFFICE.

EDGAR G. THOMSEN, OF WINONA, MINNESOTA.

SEALING DEVICE.

Application filed October 1, 1927. Serial No. 223,359.

My invention relates to sealing devices and refers particularly to devices of this character suitable for application to containers having a removable closure.

5 One of the objects of my invention is a device which will act to retain a closure within a container and which will also serve as a warning when the container has been opened after its original closure and sealing.

10 There is always a danger that closures, whether they be corks or hinged devices, may become dislodged during handling and shipment, thus causing a loss of the contents of the containers, and hence, some locking means 15 for retaining the closure means in position is highly advantageous.

There is a further danger that the closure be opened, the contents of the container removed and the container filled with different, 20 or inferior, contents, and hence, a means warning of such a tampering of the container and its contents is most valuable.

A consideration of my specification and its accompanying drawings will show that 25 the device of my invention possesses the above-mentioned, and other, valuable features.

In the accompanying drawings, illustrating 30 one form of the device of my invention, similar parts are designated by similar numerals.

Figure 1 is a front view of one form of my device attached to a container partly in section.

35 Figure 2 is a side view of Figure 1.

Figure 3 is a top view of Figure 1.

Figure 4 is a top view of my sealing device.

Figure 5 is a side view of my locking device.

40 The particular form of the device of my invention, shown in the accompanying drawings with its application to a container closure, comprises the neck 10 of a bottle, or container, (not shown), having an extended concaved flange 11 around the upper portion thereof, said flange having a plurality of recesses 12, 12. A cork 13 is positioned within the container neck 10.

45 A wire locking member consists of the portion 14 abutting upon the top of the cork 13, the two extended portions of the locking member being bent downwardly 15, 15, then downwardly and outwardly 16, 16 to be positioned under the recesses 12, 12 of the flange 55 11, the hooked extremities 17, 17 being posi-

tioned below and abutting upon the concaved flange 11, to retain the cork 13 in position.

A pliable sealing member consisting of paper, fabric, or other suitable material, has a central member 18 and two extended wings, 60 or extensions, 19, 19.

I prefer to have the sealing member carry an adhesive upon one face thereof, but an adhesive can be applied when the device is placed in position, if desired. 65

The application of my device, as illustrated, is as follows:—

The cork 13 is positioned within the neck 10 of a bottle and the wire locking member placed in position, as shown, the portion 14 70 abutting upon the top of the cork 13, the members 16, 16 being within the recesses 12, 12 and the hooks 17, 17 protruding into the concaved flange 11. The locking member thus holds the cork 13 firmly in position, and the latter can not be removed without springing the two members 16, 16 outwardly sufficiently to release the hooks 17, 17. 75

The portion 18 of the sealing member is placed over the wire 14 and the top of the cork 13 and adhesively attached thereto, the two wings 19, 19 are then bent downwardly over the wires 15, 15 and adhesively attached to the side of the cork 13. 80

In order to release the cork 13, when assembled as described, it is necessary to bend the wires of the locking member outwardly a sufficient distance to tear the sealing members 19, 19, thus disclosing that the container has been opened. 85

It will thus be seen that my device acts not only as a means for retaining a cork from accidental displacement, but also serves as a warning, or notice, when the container has been opened after its original sealing. 90

The portion 18 of the sealing member may be used for advertising, or such other printed notice as may be desired. 95

I do not limit myself to the application of 100 my device to bottle neck flanges having recesses within which my locking members may be positioned, as shown, as my device may be applied successfully to bottle neck flanges having no such recesses and in which my device is maintained in position by contact between its hooked extremities and the power portion of the concave neck flange. 105

I do not limit myself to the particular size, shape, number, arrangement, or material, of parts, as shown and described, as these 110

are given simply as a means for clearly describing the device of my invention.

What I claim is:—

1. In a sealing device capable of attachment to a container having a neck, in combination, a container, a neck to said container, a flange to said neck, a closure for said neck, a metallic locking member abutting upon said closure and locking beneath said flange and 5 a pliable sealing member abutting upon and exterior of the locking member and attached adhesively to the top and sides of the closure.
2. In a sealing device capable of attachment to a container having a neck, in combination, 15 a container, a neck to said container, a flange to said neck having a plurality of recesses therein, a closure for said neck, a metallic locking member abutting upon the upper face of said closure, positioned within said recesses 20 and locking beneath said flange and a pliable sealing member abutting upon and exterior of the locking member and attached adhesively to the top and sides of the closure.
3. In a sealing device capable of attachment to a container having a neck, in combination, 25 a container, a neck to said container, a flange to said neck, a cork within said neck, a metallic locking member abutting upon the upper face of said cork locking beneath said flange and a pliable sealing member abutting upon and exterior of the locking member and attached adhesively to the top and sides of the cork.
4. In a sealing device capable of attachment to a container having a neck, in combination, 35

nation, a container, a neck to said container, a flange to said neck having a plurality of recesses therein, a cork within said neck, a metallic locking member abutting upon the upper face of said cork, positioned within said recesses and locking beneath said flange and a pliable sealing member abutting upon and exterior of the locking member and attached adhesively to the top and sides of the cork. 40

5. In a sealing device capable of attachment to a container having a neck, in combination, a container, a neck to said container, a flange to said neck, a cork within said neck, a metallic locking member abutting upon the upper face of said cork, locking beneath said flange, a paper sealing member abutting upon and exterior of the locking member and adhesively attached to the top and sides of the cork. 45

6. In a sealing device capable of attachment to a container having a neck, in combination, a container, a neck to said container, a flange to said neck having a plurality of recesses therein, a cork within said neck, a metallic locking member abutting upon the upper face of said cork, positioned within said recesses and locking beneath said flange, a paper sealing member abutting upon and exterior of the locking member and adhesively attached to the top and sides of the cork. 50

Signed at Winona, in the county of Winona and State of Minnesota, this 27 day of September, 1927.

EDGAR G. THOMSEN.
